LOOM FOR WEAVING TUFTED PILE FABRICS

Isaac Bradley Bassindale, Oldham, England, assignor to Platt Brothers and Company Limited, Oldham, England

Application September 13, 1950, Serial No. 184,551
In Great Britain September 15, 1949

2 Claims. (Cl. 139—336)

1

This invention of improvements in looms for weaving tufted pile fabrics relates to the transferring mechanism for disengaging and removing tube frames from the carrying chains of a spool Axminster carpet loom, transferring them to the place where tuft yarns are inserted between warp threads, and restoring the tube frames to the carrier chains.

Tube frames with guide tubes for the tuft yarn and spools of tuft yarn are each suspended from the carrier chains by means of spring-influenced hooks pivotally mounted on end plates at opposite ends of the tube frame.

The said hooks, hereafter for convenience referred to as chain-hooks, are mounted on the tube frame end plates in such manner as to be capable of projection and retraction laterally and are each furnished with a projection or tail extending laterally within the tube frame to form a hinge on which the hook may be retracted and disengaged from the carrying chains by the clasps.

It sometimes happens that a chain-hook becomes damaged, e. g., by rough usage of a tube frame when out of the loom, and is distorted out of correct position so that when the transferring arms operate on the clasps to release the chain-hook the catch does not properly leave the chain and the tube frame jams and, failing to leave the chains, holds up the transferring arms with resultant damage to the loom.

To avoid this happening I provide an electrical stop motion device of the type described in the specification filed with co-pending application for Letters Patent No. 150,272, filed March 17, 1950, adapted to be brought into operation to stop the loom should a tube frame jam and prevent the downward movement of the transferring arms.

The present invention consists in electrically operated stop motion means of the type referred to for the transferring mechanism for the tube frames of a spool Axminster carpet loom in combination with means for bringing said stop motion into operation including a lever mounted on the pivot shaft of said transferring mechanism and adapted to oscillate with said shaft in the movement of the transferring arms, and a spring-influenced plunger located in the path of movement of said lever and secured to the loom frame but insulated therefrom, said plunger forming one terminal contact in the low voltage electrical circuit of the stop motion, the other terminal of which is formed by the loom frame.

2

The said electrical stop motion means is characterised in that the cam-operated switch in the low voltage electrical circuit of the stop motion is opened during the initial upward movement of the transferring arms whereby to maintain the low voltage electrical circuit open during the normal working of the loom even when the contacts are bridged at the end of the upward movement of the transferring arms and is not closed until after the said contacts have been opened in the descent of the transferring arms so that the circuit is still open and not until the contacts are maintained closed by failure of the transferring arms to descend followed by the subsequent closing of the cam-operated switch is the low-voltage circuit completed to bring about stoppage of the loom.

The invention will now be described with the aid of the accompanying drawings in which only so much of a spool Axminster carpet loom is shown as is necessary for a clear understanding of the invention.

In the drawings Fig. 1 is a fragmentary side elevation of the transferring mechanism of a spool Axminster carpet loom with the invention applied thereto, the transferring arms being shown moving downwards and carrying the tube frame; Fig. 2 is a plan of Fig. 1; Fig. 3 is a side elevation, and Fig. 4 a plan, drawn to a larger scale, of a spring-influenced contact terminal shown in Fig. 1 and later to be described.

Referring to Figs. 1 and 2 of the drawings, 10 indicates a part of the loom frame; 11 a chain wheel sprocket; 12 the carrying chain; 13 one of the transferring arms; 14 a shaft on which the transferring arms are pivoted; 15 clasping means, and 16 a tube frame, all these parts being of known construction and operating in known manner.

40 In a practical embodiment of the invention as applied to a spool Axminster carpet loom, and illustrated in the drawings, I provide on the pivot shaft 14 of the tube frame transferring arms 13 a lever 17 adapted to oscillate with the said shaft 14 in movement of the transferring arms 13. Located in the path of movement of the lever 17 is a spring-influenced plunger 18 secured to the loom frame 10 but electrically insulated therefrom and forming one terminal contact in a low voltage electrical circuit, the other terminal of which is formed by the loom.

The plunger 18 is slidably mounted in lugs projecting from a bracket 19 secured to the loom frame 10 from which it is insulated by a plate 55 20 of insulating material interposed between

the bracket 19 and the loom frame 10. The bracket 19 is secured to the loom frame 10 by screw bolts 21 penetrating insulation bushes 22 in the bracket 19, a washer 23 of insulating material being interposed between the nuts 24 of the bolts 21 and the bracket. A spring 25 serves to hold the plunger 18 in operative position.

The bracket 19 is in electrical connection with the transformer in the low voltage circuit by a lead indicated at 26.

As described in the before-mentioned specification, this low voltage electrical circuit is normally kept open by a cam-operated switch, this switch being closed when the transferring arms have made a slight initial downward movement.

In the normal working of the loom the upward movement of the transferring arms 13 would cause the lever 17 to make contact with the spring-influenced plunger 18, but, as the electrical circuit is open, due to the cam-operated switch not having yet been closed, the contact would have no effect and the loom would continue to work. In the return movement of the transferring arms 13 the lever 17 breaks contact with the spring-influenced plunger 18 before the cam-operated switch is closed and the normal working of the loom proceeds.

Should the transferring arms 13 for any reason fail to descend the lever 17 would be maintained in contact with the spring-influenced plunger 18 whereupon when the cam-operated switch is closed the low voltage circuit would be completed. Completion of said circuit serves to energise a relay which in turn operates the starter to break the electric circuit to the driving motor and bring about stoppage of said motor whereupon the loom is brought to a standstill before any damage is sustained.

The cam-operated switch in the low voltage electrical circuit is opened during the initial upward movement of the transferring arms 13 whereby to maintain an open circuit during the normal working of the loom even when the aforesaid contacts are bridged at the end of the upward movement of the transferring arms 13. 45 The cam-operated switch is not closed until after the aforesaid contacts have been opened in the descent of the transferring arms 13, therefore the circuit is still open. It is not until the contacts are maintained closed, by the transferring 50 arms 13 being prevented from descending, followed by the closing of the cam-operated switch,

that the low voltage circuit is completed to bring about stoppage of the loom.

What I claim is:

1. Electrically operated stop motion means of the type referred to for the transferring mechanism for the tube frames of a spool Axminster carpet loom and which is carried on a pivot shaft mounted in the loom frame, in combination with means for bringing said stop motion means into operation, including a lever mounted on the pivot shaft of said transferring mechanism and adapted to oscillate with said shaft in the movement of the transferring arms, a bracket secured to the loom frame but insulated therefrom, and a spring-influenced plunger located in the path of movement of said lever and slidably mounted in said bracket, said plunger forming one terminal contact of the stop motion means, the other terminal contact of which is formed by the aforesaid lever.

2. In an electrically operated stop motion means for the transferring mechanism for the tube frames of a spool Axminster carpet loom, including a transferring arm carried on a pivot shaft mounted in the loom frame which transferring arm moves upwardly and downwardly during the transferring period in the normal operation of the loom, a lever mounted on the pivot shaft and adapted to oscillate with said shaft in the movement of the transferring arm, a bracket secured to the loom frame and insulated therefrom, and a spring-influenced plunger located in the path of movement of said lever and slidably mounted in said bracket, said plunger constituting one terminal contact and said lever constituting the other terminal contact of the stop motion means, said lever being movable into and out of contact respectively with said plunger in the upward and downward movement of said transferring arm, said lever remaining in contact with said plunger if said transferring arm fails to move downwardly during the operation of the loom.

ISAAC BRADLEY BASSINDALE.
